UNITED STATES PATENT OFFICE.

CHARLES H. CLARK, OF CRAFTON, PENNSYLVANIA.

DUMP-CAR-DOOR-OPERATING DEVICE.

1,270,005.

Specification of Letters Patent. Patented June 18, 1918.

Application filed April 14, 1916. Serial No. 91,029.

To all whom it may concern:

Be it known that I, CHARLES H. CLARK, a citizen of the United States, and resident of Crafton, in the county of Allegheny and State of Pennsylvania, have invented certain new and useful Improvements in Dump-Car-Door-Operating Devices, of which the following is a specification.

This invention relates to certain improvements in hopper cars; and the objects and nature of the invention will be readily understood by those skilled in the art in the light of the following explanation of the accompanying drawings illustrating what I now believe to be the preferred embodiment or mechanical expression of my invention from among other forms, arrangements and constructions within the spirit and scope thereof.

My present invention involves in whole or in part a dump car hopper door provided with operating means, that is mechanism for opening and closing the door, and means independent of said mechanism for locking the door in closed position, and an object thereof is to provide simple and reliable locking means for such doors which is independent of the door opening and closing mechanism. This as well as other objects I attain in the device described in the specification and illustrated in the accompanying drawings forming a part of this application.

In said drawings, Figure 1 illustrates a portion of a hopper bottom car partially in side elevation and partially in central vertical section; the portion in section being taken in the plane of line 1—1 of Fig. 2, the right hand door being closed and the left hand door partially open. Fig. 2 is a vertical cross section taken on line 2—2 of Fig. 1. Fig. 3 is a central vertical longitudinal section taken in the same plane as the left hand portion of Fig. 1 but showing the door locked in closed position. Fig. 4 is a sectional view taken in the same plane as Fig. 3 but showing the door completely opened. Fig. 5 is a detail horizontal section taken in the plane of line 5—5 of Fig. 2 with the door approximately in the position as shown at the left of Fig. 1.

For the purpose of illustration, I have shown a car 1 of a well known hopper bottom type employing a longitudinally extending hollow center sill 2 dividing the car into

two series of discharge hoppers arranged side by side. Each hopper includes a lower slope or floor plate 3 extending transversely of the car and inclined longitudinally thereof and an upper sharply inclined slope or floor plate 4 with the hopper discharge of the door opening arranged to discharge longitudinally of the car and located between the lower edge of slope 3 and the lower edge of slope 4.

The opening is controlled by a door 5 arranged below the hopper and mounted to swing on a bearing shaft 6 carried at the under side of the lower edge of slope plate 4 so that the door swings longitudinally of the car and when in closed position is inclined from the vertical.

The two doors 5 for a pair of hopper discharge openings are arranged in the same plane transversely of the car and are rigidly connected together by a beam 7 secured at the outer sides of the doors and adjacent their lower edges and bridges the space between the doors. Beam 7 causes the two doors to swing and operate in unison and the central portion of the beam is located a distance below center sill 2.

The mechanism for swinging the doors to closed and open positions comprises a rotary shaft 8 arranged at their outer sides and having squared ends 9. Shaft 8 is mounted on bearing brackets 10 carried on the door and a center bearing bracket 11 carried by beam 7. Shaft 8 carries a crank arm 12, the free end of which connects with link 13 and the opposite end of link 13 connects with one end of a link 14 having its opposite end pivotally mounted on a pin 15 carried in brackets 16 secured to the sill.

The arrangement of the crank arm 12 and links 13 and 14 is such that when the doors 5 are in closed position (Fig. 3) the crank 12 depends from shaft 8 with the short link 13 extending upwardly therefrom in front of said shaft.

The doors can be swung to completely opened position (after the lock has been released) by rotating shaft 8 in the proper direction to bring the links and crank 12 into longitudinal alinement (Fig. 4) so that the links and crank act as a toggle, holding the doors in completely opened position. The doors can then be brought to closed position by rotating shaft 8 in the opposite

direction thereby breaking the toggle and in a measure winding it up on the shaft thus swinging the doors to closed position.

I provide means independent of the door opening and closing mechanism for locking the doors in closed lading sustaining position so the door opening and closing means is relieved of door and lading supporting strains and stresses and is merely called

10 upon to swing the doors without being required to hold or maintain the same in closed position.

The door locking means is arranged in the vertical longitudinal plane of the center sill and comprises a yoke or pair of arms 17 projecting from the inner side of beam 7 and at their free ends carrying a cross bolt or pin 18 suitably confined for movement in slotted bearings 19 formed in said 15 arms and a swinging lock member carried by a rock shaft 21 mounted in bearings formed in brackets 22 secured to the hopper side walls. An angle bar 23 extends transversely across the car and joins the lower 20 edges of slope 3.

One end of the lock member, which at its center is mounted on rod or shaft 21 is bifurcated or forked to provide a cam-like arm 20 which when door 5 is in open position 25 rests on top of angle 23. The lock member is also provided with a nose or arm 24 and an end 25 in alignment with arm 20 and is arranged to coöperate with a lock cam 26 fixed to rock shaft 27 mounted in bearings 30 in brackets 22 and which extending transversely of the car has squared ends.

The lock member is so arranged with respect to lock pin 18 which floats within its bearing slots that when the doors are in 35 open position the lock member will be in approximately the position illustrated by Figs. 1 and 4 and when the doors are closing the floating pin will engage the curved top face of arm 20 and by it will be raised in its bearing slots. The lock pin rides over the 40 curved cam-like face of said arm to the rear and by engaging arm 24 rocks the lock member to the position shown in Fig. 3. This takes place when the door reaches closed position.

45 The floating lock pin which may be termed a keeper at this time drops to the bottom of the recess of socket formed at the junction of arms 20 and 24 with its center 50 slightly behind the center of shaft 21. In other words during the closing movement of the door the floating lock pin is carried from in front of shaft 21 to a position to the rear of said shaft.

55 When the lock pin reaches this position the latch can then be locked in door sustaining position by rotating shaft 27 in clockwise direction to swing cam 26 downwardly against depending arm 25 of the latch to a 60 position between said arm and shaft 27 as

shown by full lines in Fig. 3. With the parts in this position the door swinging mechanism performs no door holding or locking functions, the entire burden of holding the doors closed against the pressure of the lading being carried by the locking mechanism and particularly arms 17, lock pin 18, the latch and its shaft and the lock cam 26.

The doors can be released for dumping 75 by rotating shaft 27 in counter clockwise direction. This swings cam 26 and causes the toe 29 thereof to strike upwardly against the outer end of arm 25 of the latch thereby carrying floating pin 18 over shaft 21 and 80 forwardly from locking position so that the weight of the door and the pressure of the lading will swing the door to open position as shown in Fig. 1, or possibly to completely open position as shown in Fig. 4. The opening movement of the door throws the latch down to lock pin receiving position shown by Fig. 1.

When the latch on its door releasing movement under the kick or blow of cam 26 has moved the floating pin or lock bolt, called herein a keeper, forwardly of shaft 21 the weight of the door and lading will continue the opening movement of the door or if not sufficient the shaft 8 may be rotated for this purpose. The nose 29 of the cam follows arm 25 of the latch on its upward swing so that when the lock pin leaves the latch the arm 20 thereof lies below shaft 21 and in position to receive the keeper. When keeper 18 engages the latch on closing movement of the door and swings the latch to locking position the free arm 25 of the latch will swing down into engagement with the cam 26 and will swing the same to the position shown 105 by dotted lines in Fig. 3 or will swing the same completely around to latch locking position shown by full lines Fig. 3. If the door is not closed with sufficient force to carry the cam 26 completely around to locking position the same can be moved to locking position by rotating shaft 27.

110 It is evident that various changes, modifications and variations might be resorted to without departing from the spirit and scope of my invention and hence I do not 115 wish to limit myself to the exact disclosures hereof.

What I claim is:

1. A hopper bottom car having a swinging 120 door provided with door swinging means, and mechanism independent of said means and including a floating lock pin for maintaining the door in closed position against the pressure of the lading, substantially as 125 described.

2. A hopper car having a bottom door adapted to swing open under the pressure of the lading, means for swinging said door to closed position, and a latch and floating 130

keeper for holding said door in closed position against the pressure of the lading.

3. In a hopper car having a bottom door adapted to swing open under lading pressure, a swinging locking latch carried by a portion of the car adjacent its door, a floating keeper carried by the door and arranged to engage said latch to automatically swing the same to locking position during closing movements of the door, and means for locking said latch in lading sustaining position.

4. In a car having a vertically swinging hopper door provided with a floating keeper for holding the door in closed position, a swinging latch mounted on a part of said car adjacent said door in the path of movement of said keeper and adapted to receive and be swung by said keeper during closing movements of the door, movable means for locking said latch in lading sustaining position and for moving said latch from said position, and means independent of said keeper and latch for operating said doors.

5. In a car having a hopper door adapted to move to open position under the weight of the lading and provided with mechanism for closing the door, means for holding the door in closed position including in its make up a floating pin and a swinging latch for receiving said pin and adapted to be swung thereby to door locking position.

6. In a center sill hopper bottom car having twin hopper doors provided with a cross member connecting the same below said sill and means connected to said cross member for operating said doors, means including a floating pin for holding and locking said doors tightly closed independently of said door operating mechanism.

7. Locking mechanism for the doors of hopper bottom cars comprising a floating keeper, a swinging latch coöperating therewith and means for locking said latch in locking position.

8. Locking mechanism for the doors of a hopper car comprising a pin mounted to float within supporting arms carried by the car door, a swinging latch carried by a part of the car adjacent said door formed and mounted so as to be swung by said pin during opening and closing movements of said door, and movable means for locking said latch in locking position and for swinging said latch from locking position.

9. In a center sill car having vertically swinging twin hopper doors rigidly connected together by a cross member located below the sill, a keeper carried by said cross member, a pivoted latch carried by the car and having a bifurcated end adapted to receive said keeper and a portion having a projection for coöperation with a pivoted locking member for maintaining the latch

in locking position and arranged to trip or move the same from locking position; said keeper being adapted to swing said latch to locking position on closing movements of the door.

70

10. In a center sill car having twin hopper doors connected together below said sill by a rigid cross member, a door locking agent carried by said cross member and comprising slotted arms and a floating cross bolt, a pivoted latch carried by the car arranged in the path of movement of said floating bolt and provided with means for lifting said bolt on closing movements of the doors and to be swung by said bolt to locking position wherein the axis of said bolt lies behind the axis of the latch.

80

11. In a center sill car having twin hopper doors provided with a cross member located below said sill and connecting said doors together, a rotary shaft arranged across the rear side of said doors and provided with a crank arm below said sill, a toggle link connection between said crank arm and said sill for swinging said doors to closed position, and means independent of said shaft and links for holding the doors in closed position against lading pressure.

85

12. In combination with a car having a hopper door carrying a keeper for holding the door in closed position against lading pressure, a pivoted latch carried by a portion of the car adjacent said door and having one end shouldered for engagement by said keeper on door closing movements and to be swung by said keeper into locking position, and a rotary shaft provided with a latch locking and tripping cam.

90

13. A car having a hopper door, provided with a keeper shaft having limited independent vertical play, a latch mounted and swingable on a transverse axis and recessed at one end to receive said shaft and to be swung thereby as the door is moved to closed position, said latch being arranged to swing up behind said shaft and to lift the same over and approximately drop the same to door locking position behind said axis, and means for tripping the latch to release the keeper and door, substantially as described.

105

14. A car having a vertically swingable hopper door provided with a floating lock bolt, a latch for said bolt, said latch being swingable on a transverse axis carried by a portion of the car adjacent to said door and arranged to be engaged and swung by said bolt to locking position, and a rotary locking cam adapted to hold said latch in bolt locking position and also adapted to trip said latch to bolt releasing position.

110

15. A dump car having swinging aligned twin dumping doors rigidly secured together by a cross member, a separable latch and floating bolt mechanism between said cross member and an opposite portion of the car

125

130

for holding said doors in closed position, and a rotary shaft carried by and movable with said door and having a door closing and opening connection with an adjacent portion of the car.

16. A swinging door for dump cars provided with a rotary winding shaft and connection for swinging the door to closed and to opened positions, and a separable 10 swinging latch and floating bolt mechanism for holding said door in closed lading sustaining position independently of said shaft and connection.
17. A swinging door for dump cars pro-

vided with a separable floating bolt and 15 swinging latch mechanism for holding said door in closed position against the pressure of the lading, and a rotary locking cam for said latch having a projecting nose adapted to forcibly strike and trip said latch to 20 release the floating bolt.

In testimony whereof I affix my signature in presence of two witnesses.

CHARLES H. CLARK.
